(57) **CLAIM**

The ornamental design for a beverage can capsule, as shown and described.

DESCRIPTION

FIG. 1 is a perspective view of a beverage can capsule, showing our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is an exploded perspective view thereof.

The broken lines and the areas within them depict portions of the beverage can capsule that form no part of the claimed design.
